UNITED STATES PATENT OFFICE.

BENJAMINE F. HUDSON, OF JACKSONVILLE, OREGON.

MATCH-BOX.

937,809.

Specification of Letters Patent. Patented Oct. 26, 1909.

Application filed February 11, 1909. Serial No. 477,314.

To all whom it may concern:

Be it known that I, BENJAMINE F. HUDSON, citizen of the United States, residing at Jacksonville, in the county of Jackson 5 and State of Oregon, have invented certain new and useful Improvements in Match-Boxes, of which the following is a specification.

This invention relates to match receptacles 10 and has special reference to one from which the matches are to be fed singly.

The invention has for an object the provision of a receptacle of this nature which is of such formation as to admit of the 15 positioning of matches in the same in bulk, the matches being retained within a flange while being fed into separate pockets provided for the same and eliminates the disadvantage of having to position the matches singly 20 within the device.

The invention has for another object the provision of a match receptacle which is adaptable to the pocket as well as the positioning of the same against a wall or the 25 like where it is convenient and necessary to provide a quantity of matches.

A further design of the invention is the provision of an improved feeding mechanism which is of simple and novel formation, 30 by means of which the matches are released singly from the lower end of the receptacle where they are permitted to fall into the hand of the operator or a tray provided for the same.

35 For a full understanding of the invention reference is to be had to the following description and accompanying drawings, in which,

Figure 1 is a perspective view of the match 40 receptacle as applied to a suitable holder for the same. Fig. 2 is a detailed view of the rotary bottom employed in connection with the receptacle. Fig. 3 is a detailed view of the metallic strip which forms the 45 match receiver. Fig. 4 is a vertical section through the device. Fig. 5 is a horizontal section through the device having the match receiver removed therefrom. Fig. 6 is a horizontal section of the complete device. 50 Fig. 7 is a detailed sectional view of the device disclosing a match stem being released therefrom. Fig. 8 is a detailed view of the shutter employed in connection with the device. Fig. 9 is a detailed sectional view of 55 the shutter and adjacent supporting members.

Corresponding and like parts are referred to in the following description and indicated in all the views of the drawings by the same reference characters.

Referring to the drawings, the numeral 10 designates a cylindrical casing which is provided upon the lower extremity thereof with an annular flange 11 which extends outwardly therefrom and upon which is slidably supported a bottom 12. The bottom 12 is provided with an upwardly extended and inturned flange 13 which engages the upper face of the flange 11 and supports the bottom 12 thereby. The casing 10 is provided upon its upper edge with a plurality of inwardly extended teeth 14 which are adapted to engage in apertures formed in the sides of a match receiver 15. The match receiver 15 is constructed of a strip of metal which is crimped transversely at equi-distant portions throughout its length and which is rolled upon itself into cylindrical formation. When in such rolled position the crimped portions of the metallic strip form a plurality of partitions 16 between which are positioned the matches. The outer end of the metallic strip is enlarged for the purpose of forming a wall 17 which extends upwardly beyond the edges of the partition 16 to enable the operator to more easily feed the matches into the match receiver 15. The casing 10 is provided with a cap 18 which is positioned over the upper extremity of the match receiver 15 and is secured to the casing 10 by means of ears 19 which are carried by the cap 18 and adapted for engagement in recesses 20 formed in the upper end of the casing 10.

The feeding mechanism comprises a shutter 21 which is slidably disposed in a radially formed recess in the bottom 12. The shutter 21 is provided upon its outer extremity with two tongues 22 which are disposed in parallel and which are adapted to engage upon the opposite sides of a bead 23 which is longitudinally disposed upon the lower edge of the metallic strip forming the match receiver 15. The inner end of the shutter 21, which terminates centrally of the bottom 12 is engaged between two semi-circular plates 24 and 25 which form a guideway for the shutter 21 when the same is retracted. For the purpose of supporting the outer extremity of the shutter 21 the same is provided with heads 26 and 27 which extend laterally from the shutter 21 and engage

grooves in the inner face of the bottom 12 adjacent the radial slot formed therein.

When it is desired to position the receptacle against a wall or the like for general use, the same is provided with a back 28 which is suitably apertured as at 29 for the purpose of securing the back 28 against a wall, the back 28 being provided with an outwardly extended arm 30 intermediate 10 thereof which is secured to the outer face of the flange 13 formed upon the bottom 12. The back 28 is provided with a base 31 which carries a flange 32 which is extended upwardly about the edges thereof and terminated in the back 28 to form a tray for the reception of matches which are dropped from the receptacle. The flange 32 is provided with a suitable friction surface 33 against which the matches are adapted to be engaged for the purpose of igniting the same.

The operation of the receptacle is as follows: The cap 18 is removed from the casing 10 and the operator grasps a number of matches in the hand and drops the same in the upper end of the match receiver 15, when the matches will fall within the receiver between the partitions 16. The wall 17 prevents the falling of the matches as they are positioned upon the upper end of the receiver. When it is desired to withdraw a match from the receptacle, the bottom 12 is held in rigid position while the casing 10 is rotated to cause the match receiver 15 to revolve upon the upper face thereof and to bring the match into registration with the radially formed slot in the bottom 12. As the bead 23 is spirally wound the outer extremity of the shutter 21 will be gradually fed toward the center of the bottom 12 admitting of the displacement of the matches contained in the receiver 15 as they are consecutively brought into registration with the slot disposed in the bottom 12. The intermittent rotation of the casing 10 causes the match receiver to revolve therewith and to carry the partitions 16 past the slot in the bottom 12 and to admit of the falling of the matches therethrough. It is thus seen that by continuing the intermittent rotation of the match receiver 15 that all of the matches contained therein will be brought into registration with the slot.

Having thus described the invention, what is claimed as new is:

1. A match delivering receptacle comprising a casing, a roller strip disposed in said casing, a plurality of partitions mounted between the walls of said strip to form match pockets therein, a bottom rotatably disposed on said casing, said bottom having a radially formed slot therein, and a shutter mounted in said bottom in the aperture formed

therein for releasing matches therethrough 65 from said casing.

2. A device of the class described comprising a casing, a spirally wound strip rigidly disposed in said casing, a plurality of partitions equi-distantly spaced between the walls 70 of said strip, a bottom rotatably disposed on said casing and means carried by said bottom for releasing matches singly from said casing.

3. A device of the class described comprising a casing, a rolled strip rigidly disposed in said casing, said strip being transversely crimped at equi-distances throughout its length to form partitions, a bottom rotatably disposed on said casing; a shutter slidably 80 disposed in said bottom, tongues upwardly extended from the outer extremity of said shutter and a bead formed on said rolled strip for engagement between said tongues to actuate said shutter. 85

4. A match receptacle comprising a casing, walls spirally positioned within said casing, partitions equi-distantly positioned between said walls for the reception of matches therebetween, a cap detachably disposed on said casing, a bottom rotatably positioned on said casing and a shutter slidably disposed in said bottom for engagement with the lower edges of said walls for the purpose of sliding said shutter and releasing 95 matches from said casing.

5. A device of the class described comprising a casing, walls spirally positioned longitudinally in said casing, partitions equi-distantly positioned between said walls, a 100 cap disposed on said casing, a bottom rotatably mounted on said casing, means disposed in said bottom for intermittently releasing matches from said casing, an arm radially extended from one side of said bottom, a back vertically disposed for supporting said arm, a base positioned upon the lower extremity of said back and a flange 105 upwardly extended about said base to form a tray for the reception of matches dropped 110 from said casing.

6. In a device of the class described, the combination with a casing, of a rolled strip rigidly positioned in said casing, partitions equi-distantly spaced between the walls of 115 said strip to form compartments for matches, a bottom rotatably mounted upon said casing, a shutter slidably positioned in said bottom and means for connecting said shutter to said strip for the purpose of bringing the matches consecutively into registration with a slot formed in said bottom.

In testimony whereof I affix my signature in presence of two witnesses.
